UNITED STATES PATENT OFFICE.

ALBERT JOHN FREDERICK LEE, OF WEST EALING, ENGLAND.

SUBMERSIBLE VESSEL.

1,225,662.

Specification of Letters Patent.

Patented May 8, 1917.

Application filed March 8, 1917. Serial No. 153,452.

To all whom it may concern:

Be it known that I, ALBERT JOHN FREDERICK LEE, a subject of the King of Great Britain, formerly residing in Montreal, Canada, but at present residing in West Ealing, England, have invented certain new and useful Improvements Relating to Submersible Vessels, of which the following is a specification.

10 The invention consists in a device which enables a vessel of ordinary construction to be submerged below the surface to any required depth, while at the same time the upper decks and the upper parts of the sides 15 of the vessel are surrounded by air. The submersion of the vessel can be effected at any time when it is deemed expedient, the depth of immersion can be rapidly and easily controlled, and the vessel can proceed 20 under these conditions to her destination.

The vessel is submerged by the pressure exerted on a cushion of air contained between the vessel and an outer vessel which 25 surrounds the submerged vessel both from above and on each side.

Means are provided according to the invention for readily passing from the vessel or the outer structure into the water through 30 air and water locks and for returning through the locks from the water.

The cushion of air inclosed between the vessels can be used as a reservoir of compressed air for the combustion of the fuel 35 in oil driven engines, which may be placed in either vessel or both, but which are preferably contained in the outer vessel. The storage capacity of the air cushion in a vessel of moderate dimensions, having a length, 40 for example, of 300 feet would be equivalent to about half a million cubic feet of air at atmospheric pressure. This supply can be maintained at an approximately constant pressure by compressors placed in the outer vessel and drawing in atmospheric air by 45 means of a suitably arranged pipe, raised or lowered as required.

The vessels could be propelled under all 50 conditions by internal combustion engines and no auxiliary source of motive power, such as electric accumulators, would be required.

Guns of any required caliber could be mounted in the outer vessel and when in use

could be raised in known manner on platforms by elevating gear to the level of the water; observation hoods can be similarly fitted.

The inner vessel can be utilized for storing cargo and munitions of any description and the outer vessel for the conveyance of men and cargo.

The accompanying drawings represent an example of a submersible vessel surrounded by a protecting outer structure according to the invention.

Figure 1 is a side elevation and Fig. 2 a section on the line 2—2 of Fig. 1. Fig. 3 is a longitudinal vertical section of an air lock, and Fig. 4 an end elevation of the lock.

Figs. 5, 6, 6^A and 7 show details of construction.

Referring to Figs. 1 and 2, A is a vessel submerged below the surface of the water, surrounded and protected by the vessel B of which the cross section amid ships is of the form shown in Fig. 2. At the stern of the vessel B, gates *a* (Fig. 5) pivoted on vertical hinges are opened to admit the vessel A and at the same time the frame *b* is

turned about horizontal hinges *c* into the position shown in dotted lines. When the vessel A has passed through the gates, they are closed and the frame is turned into the position shown by the full lines and bolted to the girders *b'*.

To allow the entrance of the vessel A, the vessel B is lightened as far as required, and, if necessary, the draft of the vessel A increased by the temporary admission of water ballast. The outer vessel may be connected to the vessel housed within it by cables and preferably movable booms between the two vessels so as to maintain their relative positions; fenders *d* may be fitted at intervals along the inner surfaces of the vertical sides of B to lessen any shock due to accidental impact between the vessels.

When the gates *a* are closed, the parts of the vessel A not immersed in water are surrounded on all sides by a cushion *e* of air.

In order to immerse the vessels A and B at any time below the surface of the water the space inclosed by the vertical sides of the vessel B is divided into water-tight compartments, such as *f₁*—*f₆* provided with hatches *g₁*—*g₆*. The immersion is effected by opening valves in these compartments

which release air and admit water, first from the lowest compartments and then in order from those next above; the valves for the compartments at the same level are, preferably, operated simultaneously by a sprocket wheel and chain, separate sprocket wheels being fitted for each set of valves. In order to raise the vessels, water is expelled first from the upper compartments of B by opening valves leading into the air cushion space and then similarly emptying the compartments in the reverse order from that in which they were filled. As the outer vessel B descends, the compression exerted on the air cushion *e* will cause the vessel A to descend proportionately, and, conversely, the two vessels will rise together.

If it is desired that the vessels should at any time remain at a certain depth below the surface, heavy weights, ordinarily housed in suitable recesses, may be payed out by cables passing around winches until they ground, when the increased buoyancy of the vessels will cause them to rise to a level which can be controlled by winches *h*₁ and *h*₂; or anchors *k*¹ and *k*² can be let go and the vessels, lightened by the ejection of water ballast, allowed to rise to the required distance from the surface, or again, horizontal propellers may be provided to keep the vessel practically constant at the required depth.

The air for the combustion of the fuel of the internal combustion engines *i*₁, *i*₂ is supplied to the engine room compartment directly from the air cushion *e* through valves which allow a steady pressure to be maintained, irrespective of any changes in the local conditions due to alterations of pressure in the air space, or to fluctuations in the action of air compressors *j*, which are provided for various purposes.

In order to renew the air forming the cushion *e*, and to compensate for the amount used in the engines, a pipe *l* is connected by a swivel water-tight joint at *l*₂ to a fixed casing *l*₃. The free end of the pipe *l* carries a float *l*₁ and is bent as shown. Preferably, the pipe is branched into two parts above the flexible elbow at *l*₄, the two open ends being secured to the same float. A valve *l*₅ at the upper part of the casing *l*₃ is normally in the raised position shown in Fig. 6^A, in which a catch *l*₇ connected by a cord *l*₆ to the valve *l*₅ engages over a valve *l*₈ at the bottom of the casing, opening upward. Should water enter the pipe *l* through the open ends attached to the float *l*₁, the valve *l*₅ turns about its hinge *l*₉ so as to close the casing as shown in Fig. 6, and at the same time the catch *l*₇ is released. Air in a pipe *l*₁₀ which is connected to the pressure end of the compressors lifts the valve *l*₈, thereby returning the air to the compressor room and preventing the forma-

tion of a partial vacuum therein. The valve *l*₅ can be opened by an extension *l*₁₁ of the cord *l*₆.

It is advisable when vessels are proceeding under water that the exhaust gases should be ejected in such a manner that there is not a constant stream of gaseous bubbles rising in the wake of the vessels and disclosing their path to the enemy. For this reason it has been previously proposed to lead the burnt gases into a reservoir from which they can be ejected automatically or by hand at irregular intervals of time.

In the present arrangement the burnt gases are led into a chamber D from which they are drawn by an air compressor and forced into an under water compartment D₁ provided at the stern of the vessel B (Fig. 5).

When the pressure in the compartment D₁ has attained a given value a valve *m* on the side of the vessel B is automatically opened and the gaseous mixture rapidly expelled from the compartment. According to the invention any water entering the compartment is forced out, after the valve *m* has automatically closed, through a bent bleed pipe *n* (Fig. 5), one end of which opens at the bottom of the compartment D₁ and the other end dips under the surface of the water. A ball float valve of known type closes the inlet to the pipe and prevents the escape of air or gas, if the water level in the compartment uncovers the mouth of the pipe, but leaves the inlet open, if the water level is above the inlet.

At *o*₁, *o*₂ are observation hoods, one of which is shown on a larger scale in Fig. 7.

The hood *o*₁ is provided with a hinged glass cover *p* and dead lights around its walls and can be elevated in the fixed casing *q* by suitable lifting gear operated by air or water pressure or mechanically. A door *r* is arranged to give entrance to or exit from the hood through the doors *r*₁ or *r*₂ in the fixed casing *q* in either the elevated or lowered position of the hood. Should a sea be shipped when the cover *p* was in the raised position, as shown by the dotted lines, closing the cover *p* opens a valve *s*, normally closed by a spring *t* and allows the water to escape and air to enter.

Guns may be mounted in larger hoods or turrets such as *u* which can be raised and lowered in the same way as the smaller hoods *o*₁ or *o*₂.

Gang ports *v*₁, *v*₂, *v*₃ are provided for removing cargo or stores from the outer vessel B or the inner vessel A.

Hatch covers are shown at *w*₁, *w*₂, *w*₃ (Fig. 1) and at *w*₄, *w*₅ (Fig. 2).

Figs. 3 and 4 represent an arrangement of air locks provided in the submersible vessel B, preferably at the bow as well as at the stern. The locks enable divers at any

time to make examination of the hull, to remove any chains or other impediments which may interfere with the action of the propeller and generally to facilitate the operations of a submarine vessel.

The lock is provided with doors and valves. In order to pass from the interior of the vessel to the water outside, compartment Z is entered, door 7 is closed; valves 5 and 6 should be kept closed. When door 10 7 and valve 10 have been closed, sea cock 9 should be opened slightly to allow the entering water to slowly fill the compartment Z, valve 4 is then shut and door 8 communicating with the sea opened.

In order to return to the vessel from the sea, compartment Z is entered, door 8 and sea cock 9 closed, valve 10 is opened and then valve 4 is also opened, the air from the interior of the vessel entering as the water leaves through goose neck pipe 11 into a well 12. A slight air pressure can, if necessary, be applied to the compartment through the valve 3. When the compartment Z is cleared of water, valve 10 is shut and the interior of the vessel gained through door 7.

Sufficient air must be supplied to the well 12 through valve 13 which is in communication with air pipes from the compressors to drive the water level below the mouth of the pipe 11.

The system of air locks described has the advantage that the air forced into the compartments would in the operation of the lock be returned to the vessel, so that none, or but very little, would be wasted by escaping externally.

It is obvious that many of the mechanical details described in connection with the example illustrated may be varied without departing from the main features of the invention.

The vessel B would normally be on the surface of the water, but if there were any danger from hostile forces, it would be immersed until its upper surface was almost down to the water level, or, as shown in the drawings, submerged below it. The device 45 would enable troops to be conveyed to an enemy's shore or through a dangerous area with great security.

The invention would also be of great assistance in the repair or salving of a sunken vessel.

In such cases the outer vessel B would be immersed so as to settle over and inclose the sunken vessel; operations could then be carried out to repair the vessel or by the attachment of chains and the like to raise it to the surface. The workmen in the air space between the two vessels could carry out the necessary operations with comparative freedom and without the assistance of divers.

Having thus described the nature of the said invention and the best means I know of carrying the same into practical effect, I claim:—

1. A submersible vessel, the cross section of which amidships has approximately the form of an inverted U, and a second vessel housed between the sides and bottom plating of the outer vessel and separated from it by a cushion of air.

2. A submersible vessel, the cross section of which amidships has approximately the form of an inverted U, the limbs of which are divided into water-tight compartments, means for filling these compartments with water ballast and for emptying the compartments, and a second vessel housed between the sides and bottom plating of the outer vessel and separated from it by a cushion of air.

3. A submersible vessel, the cross section of which amidships has approximately the form of an inverted U, a second vessel housed between the sides and bottom plating of the outer vessel and separated from it by a cushion of air, internal combustion engines provided in one of the said vessels for propulsion and means for supplying the engines with air for combustion from the air cushion between the vessels.

4. A submersible vessel, the cross section of which amidships has approximately the form of an inverted U, a second vessel housed between the sides and bottom plating of the outer vessel and separated from it by a cushion of air, air compressors for supplying air as required to the said air cushion and means for obtaining this supplementary supply of air from above the surface of the water.

5. A submersible vessel, the cross section of which amidships has approximately the form of an inverted U, a second vessel housed between the sides and bottom plating of the outer vessel and separated from it by a cushion of air, air compressors for supplying air as required to the said air cushion, and a swiveling tube connected to a float resting on the surface of the water for obtaining this supplementary supply of air.

6. A submersible vessel, the cross section of which amidships has approximately the form of an inverted U, a second vessel housed between the sides and bottom plating of the outer vessel and separated from it by a cushion of air, air compressors for supplying air as required to the said air cushion, a swiveling tube connected to a float resting on the surface of the water for obtaining this supplementary supply of air, and means for automatically closing the tube if any water enters it, substantially as described.

7. A submersible vessel, the cross section of which amidships has approximately the

form of an inverted **U**, a second vessel housed between the sides and bottom plating of the outer vessel and separated from it by a cushion of air, internal combustion engines provided in one of the said vessels for propulsion, and means for intermittently discharging the exhaust gases and for expelling any water which has entered the compartment in which the gases are collected, substantially as described.

8. A submersible vessel, the cross section of which amidships has approximately the form of an inverted **U**, a second vessel housed between the sides and bottom plating of the outer vessel and separated from it by a cushion of air, and gates at the stern of the submersible vessel for admitting the second vessel.

9. A submersible vessel, the cross section of which amidships has approximately the form of an inverted **U**, a second vessel housed between the sides and bottom plating of the outer vessel and separated from it by

a cushion of air, and air and water locks in the said submersible vessel enabling a diver to have communication between the sea and the vessel.

10. A submersible vessel, the cross section of which amidships has approximately the form of an inverted **U**, a second vessel housed between the sides and bottom plating of the outer vessel and separated from it by a cushion of air, air and water locks in the said submersible vessel enabling a diver to have communication between the sea and the vessel, and means for the ejection of water from the compartments of the lock adjacent to the sea, substantially as described.

In testimony whereof I have signed my name to this specification in the presence of two subscribing witnesses.

ALBERT JOHN FREDERICK LEE.
